CLAIM

I claim the ornamental design for a light assembly, as shown and described.

DESCRIPTION

FIG. 1 is a first perspective view of a light assembly embodying the invention.

FIG. 2 is a second perspective view of the light assembly of FIG. 1.

FIG. 3 is a front view of the light assembly of FIG. 1.

FIG. 4 is a rear view of the light assembly of FIG. 1.

FIG. 5 is a first side view of the light assembly of FIG. 1.

FIG. 6 is a second side view of the light assembly of FIG. 1.

FIG. 7 is a top view of the light assembly of FIG. 1.

FIG. 8 is a bottom view of the light assembly of FIG. 1.

FIG. 9 is a first perspective view of another light assembly embodying the invention.

FIG. 10 is a second perspective view of the light assembly of FIG. 9.

FIG. 11 is a front view of the light assembly of FIG. 9.

FIG. 12 is a rear view of the light assembly of FIG. 9.

FIG. 13 is a first side view of the light assembly of FIG. 9.

FIG. 14 is a second side view of the light assembly of FIG. 9.

FIG. 15 is a top view of the light assembly of FIG. 9; and, FIG. 16 is a bottom view of the light assembly of FIG. 9. The broken lines showing in the drawings are for the purposes of illustrating portions of the light assembly and form no part of the claimed design.

The light assembly is shown with a symbolic break in its length. The appearance of any portion of the article between the break lines forms no part of the claimed design.
